CLAIM

The ornamental design for a lanyard, as shown and described.

DESCRIPTION

FIG. 1 is a top front perspective view of a lanyard showing our new design;

FIG. 2 is a bottom rear perspective view thereof;

FIG. 3 is a top view thereof, the bottom view being a mirror image thereof;

FIG. 4 is a side view thereof;

FIG. 5 is another side view thereof;

FIG. 6 is a front view thereof;

FIG. 7 is a rear view thereof; and,

FIG. 8 is an enlarged view of a portion of FIG. 1 shown separately for convenience of illustration.

1 Claim, 6 Drawing Sheets
